UNITED STATES PATENT OFFICE.

JAMES A. KEYES, OF NEW YORK, N. Y.

SOAP-PRESS.

No. 910,543.

Specification of Letters Patent.

Patented Jan. 26, 1909.

Application filed May 2, 1907. Serial No. 371,416.

To all whom it may concern:

Be it known that I, JAMES A. KEYES, a citizen of the United States, and resident of the city, county, and State of New York, have made certain new and useful Inventions 5 Relating to Soap-Presses, of which the following is a specification, taken in connection with the accompanying drawings, which form part of the same.

10 This invention relates to presses and relates especially to presses adapted for forming cakes of soap or other articles and impressing designating marks therein, feeding devices being provided to properly feed the 15 articles to and from the dies and to maintain them in alinement.

In the accompanying drawings showing an 20 illustrative embodiment of this invention, Figure 1 is a plan view. Fig. 2 is a vertical section along the line 2—2 of Fig. 1. Fig. 3 is a similar section along the line 3—3. Fig. 4 is a vertical section along the line 4—4. Fig. 5 is a partial section showing the slide and die. Fig. 6 is a similar partial view 25 showing the parts in different position to illustrate the feeding of the articles. Fig. 7 is a partial plan view for this purpose.

In the illustrative embodiment of this invention shown in the drawings, a rigid frame 30 is formed by the supports 1, 2 which are firmly braced together by the transverse members 16. Suitable bearings 5, 6 are provided in this frame for the drive shaft 4 which may have the drive pulley 3, if desired, to operate the machine. The die cams 35 7, 8, may be mounted on this shaft 4 as well as the supply pinion 47 meshing with the gear 46 on the stub shaft 45 so as to operate the sprocket chain 44 and rotate at the desired speed the sprocket wheel 43 connected 40 to the supply drum 35 shown in Fig. 3. In this way the supply belt 68 is operated at the desired speed, the belt passing over the idle pulley 36 indicated and feeding a series of articles forward between the guides 34, 37 shown in Fig. 1, so that the foremost of these articles engages the aliner 87 which may be arranged transversely across the path of these articles, the guide 37 being preferably 45 adjustably mounted by the slotted ears 38.

The cam shaft 12 may be mounted in suitable bearings 11 secured to the frame and driven from the drive shaft by the bevel gears 9, 10, this shaft preferably carrying 50 the feeding cam 13 and oscillating cam

15 to operate the feeder. The feeder 23 may be mounted in a suitable bearing 39 adjacent one end of the table 66 and in the bearings 26 which may have the construction shown in Fig. 4. In that figure a 60 bushing 28 is shown as engaging these bearings and held in longitudinal alinement therewith by the collar 27 secured to the bushing in any desired way. This bushing preferably has a non-circular hole extending 65 therethrough with which the correspondingly shaped end 24 of the feeder engages so as to freely reciprocate in the bushing, but be held against relative rotation with respect thereto. The arm 70 is secured to this bushing 70 and is provided with a suitable follower 71 engaging a suitable groove in the oscillating cam 15, so that as this cam rotates the arm and the connected bushing and feeder are correspondingly oscillated.

The reciprocating cam 13 is provided with a cam groove engaged by a suitable roll on the lever 14 which as indicated in Fig. 4 may be mounted on the pivot 88 and pivotally connected at its upper end with the link 30 80 pivoted to the collar 29 on the feeder so that in this way the feeder is longitudinally reciprocated to the desired extent at the same time that it is oscillated by the mechanism described.

The slides 18, 19, are preferably mounted in suitable grooves in the ways 17 so as to be accurately guided in their movement, the slide 18 being provided as indicated in Fig. 2 with the head 22 to which the rear die 69 is 90 secured in any desired way. The slide 19 is shown as provided with a similar head 21 to which the front die 64 may be secured. The slide 19 is reciprocated by the follower 48 secured to the lug 63 in the slide and having 95 the roll 89 secured thereto and coöoperating with a cam groove in the die cam 8. The slide 18 has a similar lug 62 to which the follower 49 may be pivotally connected, the roll 50 on this follower engaging the cam 100 groove 60 in the cam 7, the follower being preferably guided by having a yoked end on either side of the guide block 61 supported by the drive shaft 4, as seen in Fig. 2.

If desired, a suitable recess may be formed 105 in the cam groove 60 so that when the final compression movement of the dies takes place the rear die is not positively operated by the roll which has considerable back-lash in this part of the cam groove 60, the die be- 110

ing yieldingly supported so as to prevent excessive pressure on the article within the die casing 20. This yielding action may be effected by a suitable spring buffer mounted on the frame and coöperating with a lug 55 on the slide, this buffer preferably comprising the head 56 engaged by the spring 57 and having its stem 53 passing through the adjustable sleeve 89 which may have threaded engagement with the yoke 51. Suitable nuts 52 may be used on the stem to prevent the excessive outward movement of the head.

The row of articles, such as cakes of soap 72, may be supplied to the belt 68 and fed along the same between the guides until the foremost cake is brought into engagement with the aliner 87. Thereupon further forward movement is prevented and the supply belt may under these conditions slip beneath the articles. The feeder is thereupon oscillated into its inactive position so that its blades 58, 67, on the arms 31, 32, are withdrawn from the path of the articles on the table 66 and moved into the raised position indicated in Fig. 4. Thereupon the feeding cam and connections reciprocate this feeder into its rearward position, where the blades are brought on either side of the article 72 in engagement with the guide 37. At this time the oscillating cam and arm operate and the feeder blades are swung downward on either side of this article, as indicated in Fig. 6, the detacher 77 thereupon engaging the article which has just been acted upon by the dies and forced out from the die casing 20 as the front die recedes into the position indicated in Fig. 7. This detacher may be yieldingly connected with the feeder by having its stem 74 pass loosely through an opening in the guides 75 secured to the extension 33 of arm 31, a suitable spring 76 being provided within this guide to normally hold the detacher downward with the desired force. The engagement of this spring detacher with the article effectually disengages it from the rear die and forces it down slightly so that it engages with the table 66. Thereupon the feeder is reciprocated in a forward direction carrying the article 72 forward along the table into alinement with the die casing and dies, also moving the preceding articles along the table. In this way each article is accurately fed forward by the feeder and alined with respect to the dies, the forward movement of the feeder taking place while its blades are oscillated into their lower position so as to engage the articles while its rearward reciprocation takes place while the feeder has been raised out of the path of the articles. After moving along the table 66 the completed articles may pass upon the discharge belt 72 operated by a suitable pulley 73 on the cam shaft by which they may be conveyed to any desired receiving or packing mechanism.

Having described this invention in connection with an illustrative embodiment thereof, to the details of which it is not, of course, to be limited, what is claimed as new and what is desired to be secured by Letters Patent is set forth in the appended claims.

1. In presses, a drive shaft having die cams thereon a cam shaft operated from said drive shaft, guides and an aliner, a supply belt operated from said drive shaft to feed a series of articles between said guides and bring the foremost article into contact with said aliner, slides carrying dies and operated from said die cams, a die casing with which said dies coöperate, a yielding buffer coöperating with one of said slides to give a spring yielding resistance to the corresponding die at the time of active compression, said buffer comprising an adjustable sleeve, a head loosely mounted in said sleeve and a spring between said head and sleeve, a feeder having longitudinal and oscillating movement mounted in bearings to coöperate with said aliner and said dies, a bushing, arm and oscillating cam on said cam shaft connected with and oscillating said feeder, means to reciprocate said feeder in unison with its oscillation and blades and a detacher mounted on said feeder to intermittently move into the path of articles in contact with said aliner and feed the same into the path of said dies, said detacher engaging the articles after the action of said dies thereon and detaching the same from said dies.

2. In presses, a drive shaft having die cams thereon, a cam shaft operated from said drive shaft, guides and an aliner coöperating therewith, means to feed a series of articles between said guides and bring the foremost article into contact with said aliner, dies and means to operate said dies from said die cams, a feeder having longitudinal and oscillating movement and coöperating with said aliner and said dies, means to oscillate said feeder from said cam shaft, means to reciprocate said feeder in unison with its oscillation and a blade and detacher mounted on said feeder to intermittently move into the path of articles in contact with said aliner and feed the same into the path of said dies, said detacher engaging the articles and detaching them from the dies after action thereon.

3. In presses, an aliner, means to feed a series of articles to bring the foremost article in contact with said aliner, dies to engage said articles, a feeder having longitudinal and oscillating movement and coöperating with said aliner and dies, and a blade and detacher mounted on said feeder to intermittently move into the path of articles in contact with said aliner and feed the same into coöperation with said dies, said detacher engaging the articles and detaching them from the dies after action thereon.

4. In presses, coöperating dies to act upon an article, means to operate said dies, a spring yielding buffer stationarily supported upon the frame adjacent one of said dies and 5 coöperating with said die to exert a spring yielding resistance thereto at the time of active compression, said buffer comprising a head having a limited movement and means to adjust the extent and intensity of the 10 spring-yielding action of said head.

5. In presses, means to feed and aline a series of articles, coöperating dies to act on said articles, a feeder mounted to have longitudinal movement at substantially right angles 15 to the original line of feed of said articles, means to give said feeder a transverse movement in unison with its longitudinal movement to maintain it in the path of said articles during its forward movement and to 20 withdraw it from said path during its rearward movement and a detacher on said feeder to engage said articles and detach them from the dies after being acted upon thereby.

25 6. In presses, means to feed a series of articles, coöperating dies to act on said articles, a feeder having longitudinal movement at an angle to the line of feed of said articles, means to give said feeder a transverse movement in unison with its longitudinal movement to bring said feeder into the path of said articles during its forward movement and to withdraw it from said path during its rearward movement and a detacher mounted 30 on said feeder to engage and detach articles 35 from said dies after being acted upon thereby.

7. In presses, means to supply a series of articles to be fed to dies, coöperating dies to act on said articles, a feeder having longitudinal movement at an angle to the line of feed of said articles, and means to give said feeder a transverse movement in unison with its longitudinal movement to bring said feeder into the path of said articles during its 40 forward movement and feed said articles to 45

said dies and to withdraw it from said path during its rearward movement.

8. In presses, coöperating dies to act upon articles, a feeder having longitudinal and oscillating movement and coöperating with 50 said dies, a bushing, arm and oscillating cam connected with and oscillating said feeder, means to reciprocate said feeder in unison in its oscillation and feeding means on said feeder to intermittently move into the path 55 of articles and feed the same into coöperation with said dies, said feeding means being oscillated out of the path of said articles as the feeder is reciprocated rearward.

9. In presses, coöperating dies to act upon 60 articles, an aliner and feeding means to feed a series of articles to bring the foremost article in contact with said aliner, a feeder having longitudinal and transverse movement and coöperating with said aliner and dies to supply 65 articles thereto and feeding means on said feeder to intermittently move into the path of articles in contact with said aliner and feed the same into coöperation with said dies, said feeding means being moved out of 70 the path of said articles as said feeder moves rearward.

10. In presses, coöperating dies to act upon articles, and means to operate said dies comprising a buffer stationarily supported 75 adjacent one of said dies and coöperating therewith at the time of active compression, said buffer comprising an adjustable sleeve, a head loosely mounted in said sleeve and having a limited movement with respect thereto 80 and a spring between said head and sleeve said means to operate said dies comprising a loose connection with the die with which said buffer coöperates at the time said buffer comes into action.
